UNITED STATES PATENT OFFICE.

PETER HAYDEN, OF PITTSBURG, PENNSYLVANIA.

IMPROVEMENT IN LAMPS.

Specification forming part of Letters Patent No. 36,649, dated October 14, 1862.

To all whom it may concern:

Be it known that I, PETER HAYDEN, of the city of Pittsburgh, Allegheny county, and State of Pennsylvania, have invented a new and useful Improvement in Lamps; and I do hereby declare that the following is a full, clear, and exact description of the construction and operation of the same, reference being had to the accompanying drawings, making a part of this specification.

In the different figures like parts of the burner are represented by the same letters.

Figure 1 represents a vertical central section of the burner, and shows the mode of operating the sliding wick-tube. Fig. 2 represents a horizontal projection of the burner with the upper and inner caps removed, and shows the chimney-ring and clasp and the position of the wick-tube, and the wheels for operating the wick-tube and wick at the base of the burner. Fig. 3 represents the mode of attaching the auxiliary wick and the operation of the principal wick. Fig. 4 represents a perspective of the burner placed upon a lamp, and shows the shape of the upper cap.

a a represents the base or basket-like part of the burner, which is perforated for the admission of air, and includes the chimney-ring, when that is used.

b b represents a cone or cap attached to the base by means of spring-catches, as shown at *p p p*, and is divided at the top into four parts. Two opposite parts are bent outward and form projections, as shown at *c c*. The other two opposite parts are about the width of the wick-tube at the base, and somewhat semicircular at the top, convex on the outside, and inclined toward each other, forming the mouth of the burner, as shown at *d*.

c c shows the projections of the cap *b*.

d shows the mouth of the cap *b*.

e e represents the inner cap or cone, which covers the pinion-wheels. The upper part extends nearly to the base of the mouth of the cap *b*. The wick-tube passes through it, leaving a small crevice at each side for the passage of vapor and gases from the body of the lamp directly into the flame, thus preventing the escape of unconsumed gases. This cap is circular at its base and a flattened cone fitting the wick-tube at its edge at the top.

f represents the wick-tube. It is perforated

on one side, so that the cogs of the pinion-wheel work into it for raising or lowering the wick-tube. On the other side there are two strips cut out of it to give play to the wheels running the wick. The strip remaining between the wheels is bent inward at the bottom for the suspension of an auxiliary wick, which may be common candle-wick or fluid-wick, as represented at *l m l*.

g represents the pinion for operating the wick-tube.

h represents the pinion for operating the wick.

i I represent a wire clasp for holding the chimney. It is hinged in the middle, and bent as shown at *i*, and it extends only about two-thirds around the chimney-ring, and clasps on its edges, as shown at *n n*. It can be thrown back, as in Fig. 4, and clasped on after the chimney is inserted.

k represents the principal wick.

l l represent the auxiliary wick.

m represents the hook for the suspension of the auxiliary wick.

o o o represent three ridges for the chimney to rest upon.

n n represent the clasps of the chimney-holder.

p p p represent the spring-catches for holding the cap *b*.

q represents the collar of the burner, which is fastened to the lamp.

r r represent the lamp in perspective.

s s represent an open space in the base of the burner, to form a connection between the lower chamber of the burner and the font of oil, and thus preventing the accumulation of heat in this part of the burner, and condensing by the cooling influence of the font below any vapors that may arise.

Having now described the burner, I will proceed to describe its operation.

This burner is designed to burn carbon or coal oil either with or without the use of a glass chimney; but it will also burn camphine, burning-fluid, whale-oil, and the other illuminating-oils. The font being supplied with oil and the burner being supplied with wick, to light the lamp raise the wick by the pinion *h* and light it. It can be ignited at any part of the mouth of the burner. The quantity of light and also the amount of draft are regu-

lated by the movements of the wick-tube and wick, both of which can be run up the mouth of the burner. The draft is increased by lowering the sliding tube in the mouth of the burner, and vice versa, and the quantity of light for each position of the sliding tube depends on the elevation of the wick above the tube. Thus a perfect control is had over the draft and light, and the burner will burn with or without a chimney. The projections *c c* serve to spread the flame, and by supplying the edges of the flame with a current of hot air from the cap *b* prevent their smoking. As a small portion of the flame rests within the mouth of the burner the light is very portable and is not easily blown out by the wind, so much so that it can be carried in the open air even with a strong draft of wind. The cap *b*, or any ordinary cap, can be used when a chimney is put on. A much shorter chimney can be used with the cap *b*, and a more mellow light obtained than with the ordinary chimney-lamps. The chimney is designed to rest on three or more ridges in the chimney-ring, to prevent it from getting too hot. The cap *b* may rest on ridges in the same way, to prevent the base of the burner from getting over-

heated. The auxiliary wick is designed to keep up a regular supply of oil on the principal wick, and when the oil is very light and the font shallow the auxiliary wick can be left out; but in coal and carbon oil much difficulty has been experienced when the oil is heavy and the font deep, and this auxiliary wick, lying in contact with the principal wick at the point *m*, is designed to remedy this difficulty. In small lamps, designed to be used entirely without a chimney, the chimney-ring can be omitted. The shape of the base *a a* is not material, so that it is sufficiently perforated. The pinion *g* may be reversed, with the handle on the opposite side from the pinion *h*. Instead of the whole tube *f* sliding, it may have a slide at its top answering the same purpose.

In the above specification I claim and desire to secure by Letters Patent of the United States—

A wire clasp extending about two-thirds around the chimney-ring, shaped and operating as described.

PETER HAYDEN.
